[57] CLAIM

The ornamental design for a floatboard/kickboard, as shown and described.

DESCRIPTION

FIG. 1 is a top plan view of the floatboard/kickboard of the present invention showing my new design with the bottom plan view being a mere image thereof;

FIG. 2 is a side elevational view thereof;

FIG. 3 is a top end view thereof;

FIG. 4 is a bottom end view thereof;

FIG. 5 is a top plan view of a second embodiment of the floatboard/kickboard of the present invention showing my new design with the bottom plan view being a mere image thereof;

FIG. 6 is a side elevational view of FIG. 5;

FIG. 7 is a top end view of FIG. 5;

FIG. 8 is a bottom end view of FIG. 5;

FIG. 9 is a top plan view of a third embodiment of the floatboard/kickboard of the present invention showing my new design with the bottom plan view being a mere image thereof;

FIG. 10 is a side elevational view of FIG. 9;

FIG. 11 is a top end view of FIG. 9; and,

FIG. 12 is a bottom end view of FIG. 9.
